(57) **CLAIM**

The ornamental design for a tire, as shown and described.

DESCRIPTION

FIG. 1 is a perspective view of a tire;

FIG. 2 is a front view thereof;

FIG. 3 is a left side view thereof; and,

FIG. 4 is a detailed view thereof.

Broken lines in the drawings used for demarcation of enlarged portions of the tire should be described in a separate paragraph preceding the claim, and as forming no part of the claim.

1 Claim, 4 Drawing Sheets

FIG. 1

FIG.2

FIG.3

FIG.4
